MARKING MACHINE

Claude A. Putnam and Charles F. Robbins, Keene,
N. H., assignors to Markem Machine Company,
Keene, N. H., a corporation of New Hampshire

Application July 7, 1937, Serial No. 152,326

9 Claims. (Cl. 101—110)

This invention relates to marking machines of the type in which the printing head is provided with a plurality of independently adjustable type wheels for printing a line of printed characters, and is also provided with auxiliary type members for printing additional lines of characters above and below the line which is printed by the type wheels.

One of the objects of the present invention is to provide a novel construction which facilitates the change of those auxiliary type members which are in the rear of the type wheels.

In these marking machines the auxiliary type members are usually carried by a supporting frame which is pivotally mounted on the printing head and is adapted to be swung out of its operative position away from the type wheels when the auxiliary type members are to be changed. This downward swinging movement of the supporting frame exposes the type members on the front of the type wheels so that they can be readily changed, but if the supporting frame carries type members situated at the rear of the type wheels it has heretofore been necessary to remove the auxiliary frame from the head in order to effect a change of such type members.

In our present invention we mount the auxiliary type members on a carriage or auxiliary frame which is slidably mounted in the main supporting frame that is pivoted to the printing head, the construction being such that when the main supporting frame has been swung downwardly away from the type wheels the auxiliary frame or carriage can be pulled forwardly, thus bringing those auxiliary type members that are normally in the rear of the type wheels into a position in front of the type wheels where a change can be easily effected.

A further object of our invention is to provide a novel construction which permits of using type members adapted to print two or more lines above or below the line which is printed by the type characters on the type wheels.

Other objects of the invention are to improve generally printing machines of this type in the manner hereinafter more fully set forth.

Inasmuch as our invention relates entirely to the printing head of a marking machine we have not thought it necessary to illustrate the complete machine but have confined the drawings to the printing head thereof.

In the drawings:

Fig. 1 is a side view of a printing head of a marking machine with parts broken out and illus-

trating our improvement, said figure showing the auxiliary type members in operative position;

Fig. 2 is a view similar to Fig. 1 but showing the supporting frame for the auxiliary type members swung downwardly;

Fig. 3 is a fragmentary sectional view illustrating the manner in which the auxiliary frame or carrier is drawn forwardly to render the rear set of auxiliary type members accessible;

Fig. 4 is a fragmentary sectional view of a printing head embodying our invention but showing a different form thereof;

Fig. 5 is a plan view of the supporting frame and auxiliary frame or carrier on which the auxiliary type members are mounted;

Fig. 6 is a section on the line 6—6, Fig. 5;

Figs. 7, 8, 9 and 10 are perspective views showing different forms of auxiliary type members;

Figs. 11, 12, 13 show some of the different imprints which can be made with a machine embodying our invention;

Fig. 14 is a sectional perspective view taken on the line 14—14, Fig. 6;

Fig. 15 is a view of the carrier or auxiliary frame that supports the auxiliary type members;

Fig. 16 is a view of the type member shown in Fig. 9 illustrating the printing surface thereof;

Fig. 17 is a fragmentary face view of auxiliary type members designed to print two lines.

Our improvements are adapted to be embodied in marking machines of different types but we have chosen herein to show it as it might be embodied in a marking machine of the type shown in Patents No. 1,974,753, September 25, 1934, or No. 2,006,302, June 25, 1935.

In the drawings, 1 indicates a printing head of a marking machine of the type shown in the above-mentioned patents and which is provided with a plurality of independently settable type wheels 2, said type wheels being rotatively mounted on a cylinder support 3. Each type wheel is formed on its periphery with a plurality of type-carrying projections 4, and recesses 32 between the recesses. Each projection has a type character 5 on its end as usual in printing machines of this character. The type characters 5 may be numerals or letters depending upon the character of the imprint which is to be made and any usual or suitable means such as a setting wheel 6 may be employed for individually setting the type wheels. It will be understood, of course, that the printing head is mounted for vertical movement toward and from a platen on which the work to be marked is supported.

As stated above the present invention relates

to that type of marking machine which embodies auxiliary type members designed to print a line or lines of characters additional to that printed by the type wheels 2.

5 In Figs. 1 to 3 we have shown one set of auxiliary type members 7 having type characters 8 adapted to print a line in front of that printed by the type wheels 2, and a second set of auxiliary type members 9 having type characters 10 adapted to print a line in the rear of that printed by the type wheels 2. These auxiliary type members 7 and 9 are mounted in a supporting frame 11 which is pivotally mounted on the shaft 12 extending transversely of the printing head in the 15 rear of the type wheels so that said frame can swing from its operative position shown in Fig. 1 into a lowered position shown in Fig. 2.

In order to provide for readily removing and replacing the rear auxiliary type members 9 when a change in the character of the printing is desired, we propose to mount the auxiliary type members on a carriage or auxiliary frame 13 which in turn is slidably mounted on the supporting frame 11 so that when the supporting frame 11 has been swung downwardly into the lowered position shown in Fig. 2 the auxiliary frame or carrier 13 may be pulled forwardly to render the type members 8 and 9 readily accessible.

30 The main supporting frame 11 is a skeleton frame having the two side members 14 that are connected at the rear by a tie rod 15 and at the front by a second tie rod 16. The tie rod 16 is mounted in ears 17 which extend upwardly from the front ends of the side rails 14. The auxiliary frame or carriage 13 is shown in Fig. 15, and it is a skeleton frame having the two side rails 18 which fit between the side rails 14 of the main frame 11 and are provided with outwardly extending flanges 19 which rest and slide on tracks 20 with which the side rails 14 of the main frame 11 are provided.

40 The side rails 18 of the auxiliary frame 13 are connected by rods 21, 22, 23, 24 on which the auxiliary type members are removably supported. At the front end of the auxiliary frame 13 each side rail 18 has secured thereto the upwardly inclined member 25 and the upper ends of said members are connected together by the rods 26. 45 27 indicates a thumb piece which is carried by the rods 26 and which forms a handle by which the carrier or auxiliary frame 13 may be moved back and forth on the main supporting frame 11.

45 Each auxiliary type member 7 is made as shown in Figs. 7 and 8. It is formed at one end with an open slot 28 adapted to receive the rod 23 of the auxiliary frame and at its rear end with a downwardly facing open slot 29 adapted to receive the rod 24. The type member is formed at one end with the head portion 30 having a convex upper face 31 of a shape to fit the concave recess 32 between the type-bearing projections 4 of the type wheel, and the type member is also formed with the inclined upper face 33 having the correct angle to lie flatly against the type character 5 of the type-carrying projection 4a which is adjacent that type-carrying projection that is in operative printing position. The type character 8 on the type member 7 may be situated closely adjacent the end of the head 30 so that when the type member is in place as shown in Fig. 1, the type character 8 of the auxiliary type member lies closely adjacent the type character 5 of the printing wheel which is in printing position.

The auxiliary type members 9 have substantially the same construction. Each member has at one end a horizontal open slot 34 to receive the rod 22 and at its other end it has a vertical open slot 35 to receive the rod 21. Each type member 9 is also formed at one end with the head portion 36 having the convex surface 37 to fit the curve of the recess 32 between adjacent type-carrying projections 4, and it is also formed with the inclined top face 38 against which the type character 5 of the type-carrying projection 4a rests when the parts are in operative position as shown in Fig. 1. The type characters 10 of the auxiliary type members 9 are situated on the under side thereof at the end having the head portion 36, and these type characters are thus situated closely adjacent the type characters 5 of the printing wheels which are in printing position.

When the parts are in operative position, as shown in Fig. 1, the auxiliary type members 7 and 9 are backed by the type wheels and thus any pressure against the type characters 8 and 10 of the auxiliary members is transmitted directly to the type wheels through the head portions 30 and 36 of said type members.

These type members 7 and 9 are removable so that any type member can be removed and replaced by another one. A change in the front auxiliary type members 7 can be made by simply swinging the supporting frame 11 downwardly into its open position shown in Fig. 2. When in such position the front auxiliary type members 7 are accessible so that anyone of them can be removed by first raising the end nearest the operator off from the rod 24 and then withdrawing the type member from the rod 23. A different type member may be placed in position by a reverse operation.

If it is desired to remove one of the auxiliary type members 9, then after the supporting frame 11 has been swung into its lowered position the operator grasps the handle 27 and pulls the carrier or auxiliary frame forwardly as shown by the full and dotted lines, Fig. 3. This will bring the type members 9 into a position in front of the type wheels 2 so that said auxiliary type members 9 can be readily removed from the auxiliary frame or replaced therein. After the desired change has been made in the auxiliary type members 9 then the auxiliary frame is slid backwardly into its operative position and the main supporting frame 11 may then be raised to bring the parts into the position shown in Fig. 1.

In order to enable the high point 39 of the auxiliary type members 9 to clear the type-carrying projection 4a when the auxiliary frame is pulled forwardly, the track 20 on which the auxiliary frame slides is formed with a depression 40 adjacent its rear end, this depression being 45 so situated that as soon as the auxiliary frame or carrier 13 has been moved forwardly a short distance the end 41 of the flanges 19 pass over the depression, thus allowing the rear end of the carrier or auxiliary frame 13 to drop downwardly 50 slightly as shown in full lines, Fig. 3. This will carry the high point 39 of the rear type members 9 below the type-carrying projection 4a of the type wheels so that the auxiliary frame can be pulled forwardly into a position to render the rear auxiliary type members 9 accessible.

The handle 27 is formed with a tail piece or latch 42 which is adapted to yieldingly engage underneath the tie bar 16 as shown in Fig. 1, thereby to hold the auxiliary frame in its opera- 75

tive position. When the auxiliary frame is to be pulled forwardly, as shown in Fig. 3, the operator presses upwardly on the handle 27 which will cause the rods 26 to flex or yield sufficiently 5 to disengage the latch 42 from the tie rod 16 and the operator can then pull forwardly on the handle and thus move the auxiliary frame into its open position.

Where the type characters 8 and 10 are situated closely adjacent the head ends of the type members 7 and 9, then the printed impression which the marking machine will make will be such as indicated in Fig. 11 wherein the line *a* is that printed by the type characters 5 of the 15 printing wheel, the line *b* is that printed by the type characters 10 of the rear type auxiliary members 9 and the line *c* is that printed by the type characters 8 of the front auxiliary type characters 7.

Sometimes it is desirable to print two additional lines on one or both sides of the line indicated at *a*, and if this result is desired then some of the auxiliary type members will have the type characters situated closely adjacent the head end, as shown in Fig. 7, and others will have the type members situated back from the front end as shown in Fig. 8. In printing the two lines by means of the type members such as shown in Figs. 7 and 8 the type members 7 shown 20 in Fig. 7 will be arranged alternately with the type members 7a shown in Fig. 8, as illustrated in Fig. 17, and the type characters 8 of the type members 7 will print the line indicated at *d* in Fig. 12, while the type characters 8a of the type member 7a will print the line indicated at *e* in 25 said Fig. 12. By making the same modification of the auxiliary type members 9 it will be possible to make a printed impression having the two lines *f* and *g* above the line *a* as shown in Fig. 12.

In Figs. 9 and 16 there is shown an auxiliary type member formed to print some design or word. This type member, which is indicated generally at 43, is formed with two side members 44, each having the general shape of the auxiliary type members 7 and 9, said side members being connected by a web or portion 45, the under face of which is formed to print the desired design or word, such, for instance, as indicated at *i* in Fig. 13. The two side members 44 are formed at one end with the open slots 46 to receive the rods 22 or 23 and at the other end with the downwardly extending open slots 47 to fit over the rods 21 or 24. These type members may be placed in or removed from the auxiliary frame or carrier 13 in the same manner that the individual type members 7 or 9 are.

If it is desired to make a printed impression including the word or design *i* and also including a line *h* situated between the design and the line *a* which is printed by the type wheels, then we may use the structure shown in Figs. 9 and 10. In Fig. 9 the type member 43 is made so that the edge 61 of the web 45 is spaced somewhat from the head end of the member and this type member 43 may be used in connection with the type member 7b such as shown in Fig. 10 to print the additional line *h*. This type member 7b is similar to the type member 7 in that it has the open slot 28 at the head end thereof and the vertical open slot 29 at the rear end to engage the rods 23, 24, and it also has the type character 8 closely adjacent the head end. The under side of the type member 7b, however, is cut away as shown at 48 to a depth equal to the thickness 70 of the web 43 so that the type member 7b may

be engaged with the rods 23, 24 at a point between the sides 44 of the type member 43, as shown by dotted lines in Fig. 1. When the type members 7b are in place the type characters 8 thereon will be situated in front of the edge 61 5 of the web 43 and said web will occupy the cut-away portion 48 of said type member. The characters 8 of the auxiliary type members 7b are thus situated closely adjacent the operative type-bearing projections 4 of the type wheels 10 and the printed impression which can be made will include the line *a* made by the type wheels, the design *i* and a line *h* situated between the design and the line *a* as shown in Fig. 13.

We claim:

1. A printing head for a marking machine comprising a plurality of independently adjustable type wheels, each having on its periphery type-carrying projections, a type-supporting frame, auxiliary type members removably supported by 20 said frame and shaped to engage and bear against the periphery of the type wheels adjacent the type-carrying projections that are in printing position, whereby the printing pressure to which the auxiliary type members are subjected is transmitted directly to the type wheels, and means securing said frame to said printing head for movement both in a vertical direction to separate the auxiliary type members from the type wheels and in a forward direction to render the auxiliary 25 type members accessible for interchanging them.

2. A printing head for a marking machine comprising a plurality of independently adjustable type wheels, each having type-carrying projections, a type supporting frame secured to said 35 head for movement toward and from the type wheels and also for forward sliding movement, and type members removably carried by said frame, said type members being shaped to engage and bear against the periphery of the type 40 wheels, whereby the printing pressure to which the type members are subjected is transmitted directly to the type wheels.

3. A printing head for a marking machine comprising a plurality of independently adjustable 45 type wheels, each having type-carrying characters on its periphery, a type-supporting frame, auxiliary type members removably carried by the frame and situated in the rear of the line of type characters on the type wheels that are in printing 50 position, each auxiliary type member being of a shape to engage and bear against a type wheel when said member is in printing position, whereby the pressure to which the type members are subjected during the printing operation is transmitted directly to the type wheels and means securing said type-supporting frame to the printing head for movement both in a vertical direction away from the type wheels and in a forward direction to bring the type members into a 55 position in front of the type wheels where said type members can be readily removed from the frame.

4. A printing head for a marking machine comprising a plurality of independently adjustable 65 type wheels, each having a plurality of printing characters on its periphery, a type-supporting frame, type members removably carried by the frame and situated both in the front and in the rear of the line of type characters on the type 70 wheels that are in printing position, each member having a shape to engage and bear against a type wheel when said member is in printing position, whereby the pressure to which said type member is subjected during the printing opera- 75

tion is transmitted directly to the type wheel and means securing said type-supporting frame to the printing head for movement both in a vertical direction away from the type wheels and in a forward direction to bring all the type members into a position in front of the type wheels.

5. A printing head for a marking machine having a plurality of independently adjustable type wheels, each having type-carrying projections on 10 its periphery and recesses between said projections, a supporting frame pivoted to the printing head, an auxiliary frame slidably mounted in the supporting frame, and auxiliary type members 15 removably carried by the auxiliary frame, said auxiliary type members having portions which are received in the recesses adjacent the type-carrying projections that are in printing position and which bear against the type wheels, whereby the pressure to which said type members 20 are subjected during the printing operation is transmitted directly to the type wheels.

6. A printing head for a marking machine having a plurality of independently adjustable type wheels, each having a plurality of type characters 25 on its periphery, a supporting frame pivoted to the printing head and movable from operative position to a position separated from the type wheels, an auxiliary frame slidably mounted in the supporting frame, and auxiliary type members 30 removably carried by the auxiliary frame, some of which type members are on the front side and some of which are on the rear side of the line of characters on the printing wheels that are in printing position when said frames are in operative position, and all of said auxiliary type members 35 having portions which engage and bear against the type wheels adjacent the type characters that are in printing position, whereby the pressure to which the type members are subjected during the printing operation is transmitted directly to the type wheels.

7. A marking machine comprising a printing head having a plurality of independently adjustable type wheels, each having type-bearing projections, a supporting frame pivoted to said printing head, said frame having spaced side rails con-

nected by rods, auxiliary type members removably supported by said rods, each type member having at one end a horizontal open slot to receive one rod and at its other end a vertical open slot to receive another rod, the top side of each auxiliary member having a shape to fit the recess between adjacent type-bearing projections.

8. A marking machine comprising a printing head having a plurality of independently adjustable type wheels, each having type-bearing projections, a supporting frame pivoted to said printing head, said frame having spaced side rails connected by rods, auxiliary type members removably supported by said rods, each type member having at one end a horizontal open slot to receive one rod and at its other end a vertical open slot to receive another rod, the top side of each auxiliary member having a shape to fit the recess between adjacent type-bearing projections, some of the type members having their type characters 20 closely adjacent the end and other auxiliary type members having their type characters spaced from said end.

9. A marking machine comprising a printing head having a plurality of independently adjustable type wheels, each having type-bearing projections, a supporting frame pivoted to said printing head, said frame having spaced side rails connected by rods, auxiliary type members removably supported by said rods, the upper face of said 30 type members having a shape to fit the recess between adjacent type-bearing projections of the type wheels, one of said auxiliary type members having two spaced sides provided with slots to receive the rods and connected by a web having a 35 printing character on its under face, and other type members having slots to receive the rods and being situated between the side members of the first-named type member, said other type members being cut away on their under side to accommodate the web of the first member and having at their ends type characters adjacent the 40 edge of said web.

CLAUDE A. PUTNAM.
CHARLES F. ROBBINS.
